UNITED STATES PATENT OFFICE.

FRANCIS M. HANNA, OF MOUNT STERLING, ILLINOIS.

ELECTRIC BELT.

SPECIFICATION forming part of Letters Patent No. 247,461, dated September 20, 1881.

Application filed July 25, 1881. (Model.)

To all whom it may concern:

Be it known that I, F. M. HANNA, of Mount 5
Sterling, in the county of Brown and State of
Illinois, have invented certain new and useful
Improvements in Electric Belts; and I do hereby
declare the following to be a full, clear, and
exact description of the invention, such
as will enable others skilled in the art to which
it pertains to make and use it, reference being
had to the accompanying drawings, which form
part of this specification.

My invention relates to an improvement in
electric belts; and it consists in attaching the
two metallic pads together by suitable adjust- 15
able connections, whereby the pads can be
moved nearer together or farther apart, so as
to bring them just opposite to each other upon
the body, and insulating the connecting parts
of the pads from the body by strips of oil-cloth,
as will be more fully described hereinafter.

The object of my invention is to provide an
electric belt in which the pads can be adjusted
relatively to each other, so that one of them
can be placed just over the diseased part and
the other pad then adjusted just opposite upon
the body, so that the current of electricity will
pass directly through the diseased part of the
body to the other pad.

Figure 1 is a plan view of the belt, taken
from the inner side. Fig. 2 is a horizontal lon- 30
gitudinal section of the same.

A represents a belt, of any suitable mate- 35
rial, which is intended to pass around the body,
and which may be provided at either one of its
ends with any suitable fastening. Secured to
this belt by means of a strip of oil-cloth, B,
are the two pads C D, which are connected to- 40
gether by means of the two strips E, the inner
ends of which strips are loosely attached
together in such a manner that the pads can
be moved freely back and forth by sliding them
on each other. These strips pass through slits
45 or openings which are cut in the oil-cloth, and
are only held in position upon the belt by the
oil-cloth, and by no other means. This oil-
cloth, being a non-conductor and interposed
between the body and the strips, prevents the
electricity from passing from the strips into

the body. One of the pads is made of zinc
and the other is made of copper, and both of 50
them are made rounding upon their edges, so
that they cannot rub or irritate the body where
they come in contact with it. Secured to the
back of each one of these pads by means of a
rivet or any other suitable device is a sheet 55
or washer, I, of oil-cloth, which serves to in-
sulate the pad from the body. The outer ends
of the connecting-strips are fastened to the
pads by means of hinged joints passing through
slits which are made in these washers, and the 60
washers are made sufficiently wide and large
to cover the ends of the strips where they pro-
ject through the oil-cloth B.

The great objection to electric belts hereto- 65
fore used has been that there has been no way
for adjusting the pads so that one of them
could be placed just upon the diseased parts
and the other one directly opposite, so that the
current from one pad would pass directly 70
through the diseased part to the other, and
hence a large proportion of the effects of the
belt has been lost. Where the belt happens
to be too long or too short, one pad can be
placed directly over the diseased parts; but 75
the other pad will be placed against the body
at such an angle that only a portion of the cur-
rent will pass through the diseased part. By
making the pads adjustable they can be ad-
justed so that the current will be passed di- 80
rectly through the diseased part.

Having thus described my invention, I
claim—

In an electric belt, the combination of the
belt A, the oil-cloth B, which covers the two
connecting-strips and holds the pads in place, 85
the two pads being adjustably connected to-
gether by suitable strips, and the washers of
oil-cloth, which are placed back of the pads,
substantially as described.

In testimony whereof I affix my signature 90
in presence of two witnesses.

FRANCIS M. HANNA.
